(57) **CLAIM**

The ornamental design for a flexible strip light, as shown and described.

DESCRIPTION

FIG. 1 is a perspective view of a flexible strip light, according to a first embodiment;

FIG. 2 is a front view of the flexible strip light, according to the first embodiment, wherein the strip light is shown in a flattened, unrolled state;

FIG. 3 is a rear view of the flexible strip light, according to the first embodiment;

FIG. 4 is a right side view of the flexible strip light, according to the first embodiment;

FIG. 5 is a left side view of the flexible strip light, according to the first embodiment;

FIG. 6 is a top view of the flexible strip light, according to the first embodiment;

FIG. 7 is a bottom view of the flexible strip light, according to the first embodiment;

FIG. 8 is a perspective view of a flexible strip light, according to a second embodiment, wherein the strip light is shown in a rolled state;

FIG. 9 is a front view of the flexible strip light, according to the second embodiment;

FIG. 10 is a rear view of the flexible strip light, according to the second embodiment;

FIG. 11 is a right side view of the flexible strip light, according to the second embodiment;

FIG. 12 is a left side view of the flexible strip light, according to the second embodiment;

FIG. 13 is a top view of the flexible strip light, according to the second embodiment; and,

FIG. 14 is a bottom view of the flexible strip light, according to the second embodiment.
